AEROPLANE TOY

John Eslinger, Chicago, Ill.

Application July 10, 1931. Serial No. 549,826

17 Claims. (Cl. 272—31)

My invention relates to improvements in the toy aeroplane disclosed in my application Ser. No. 545,209, filed June 18, 1931, wherein a miniature aeroplane travels in a circular path around a vertical pivot under the power of an electric motor located adjacent the pivot.

One object is to provide a new and improved mounting for the miniature aeroplane which reduces the number of moving parts and enables the motor and the driving parts to be enclosed to the end that the operation of the toy more closely simulates that of a commercial aeroplane.

The invention also resides in the novel construction of the support for the aeroplane and the connection for transmitting the motive power to the aeroplane.

Another object is to provide a miniature aeroplane mounted as above described in combination with a beacon light adapted to follow the aeroplane in its flight around the circular path.

A further object is to provide a novel arrangement of springs for exerting a variable counter-balancing action on the aeroplane.

Other objects and advantages of the invention will become apparent from the following detailed description taken in conjunction with the accompanying drawing in which

Figure 1 is a perspective view of an aeroplane toy embodying the novel features of the present invention.

Fig. 2 is a side elevational view of the supporting and driving mechanism with certain of the parts shown in vertical section.

Fig. 3 is a fragmentary side elevational view of a part of the supporting mechanism.

Fig. 4 is a fragmentary plan section taken through the aeroplane body in the plane of the driving shaft.

In the drawing the miniature aeroplane of the improved toy has a body 5 built around a frame 6 in which is journaled a shaft 7 carrying a driving propeller 8. The means for defining the circular path of movement of the aeroplane while

permitting the same to ascend from and descend to a supporting or landing surface includes an elongated tube which, for a purpose to later appear, is composed of telescoping sections 9 and 10 with the end of the section 9 projecting into

the side of the aeroplane slightly rearwardly of the longitudinal center of gravity of the plane. This end is surrounded by a sleeve 11 rotatable relative to the body of the aeroplane and having a bevel gear connection 12 with the propeller shaft 7. The aeroplane is thus adapted to turn

about a transverse and a substantially horizontal axis defined by the supporting tube section 9.

The opposite end of the supporting tube is mounted to turn about a vertical axis and also to tilt about an adjacent and substantially horizontal axis. Such a mounting is formed, in the present instance, by a flexible tube in the form of a helical coil 13 of wire into one end of which the tube section 10 fits snugly and is extended for a short distance, being securely held by making the tube slightly flared at its end as indicated at 14.

The other end of the coil projects through a sleeve 14 journaled in a bearing which supports the sleeve in vertical position and is itself mounted on a support preferably in the form of a casing 15 shaped to represent an aeroplane hangar. This bearing comprises a series of balls 16 disposed in raceway 17 seated between a flange 18 on the sleeve and a flange 19 depending from the under side of the hangar roof through which the sleeve 14 projects. A similarly constructed ball bearing 20 is mounted in a recess defined by a flange 20^a upstanding from the roof of the hangar. The ball raceways have horizontal and vertical surfaces so that the weight of the sleeve 14 and the parts carried thereby is sustained by the balls with a minimum friction loss while the balls at the same time provide an anti-friction bearing sustaining the lateral thrust to which the sleeve is subjected.

The intermediate portion of the coil 13 is unsupported and therefore is free to bend as shown in the drawing so as to allow the tube section 10 to tilt vertically from a substantially horizontal position shown in Fig. 2 in which the aeroplane rests on its landing surface and the position shown in Fig. 3 which corresponds to the maximum height to which the aeroplane can ascend. The horizontal axis thus provided by the flexible coils is not, it will be observed, well defined but is located approximately at the center of the unsupported section of the coil 13.

The maximum height to which the aeroplane may rise is determined by a stop at the closed end of a vertically extending slot 21 through which the tube section 10 projects. This slot is formed in an arm 22 rigid with a horizontal plate 23 which is clamped against a washer 24 by a nut 25 threading onto the upper end of the sleeve 14. The plate 23, the arm 22 and the tube supporting the aeroplane are thus adapted to turn freely as a unit with the sleeve 14.

To hold the tube section 10 against turning on its own axis, a sleeve 26 fitting loosely onto this

section and made rigid therewith by a set screw 27 is formed with flattened sides which are guided in the slot 21.

Preferably the coil 13 is formed of resilient wire 5 and wound so that it has an inherent tendency to straighten out and thereby exert a bending moment on the tube section 10 which tends to raise the outer end of the supporting tube thereby exerting a counter-balancing action on the 10 aeroplane. The magnitude of this counter-balancing action is determined by the effective length of unsupported spring between the sleeve 14 and the tube section 10 and may be varied as desired by changing the extent to which the section 15 is extended into a coil.

In order that the aeroplane may come to a stop in full flight for the purpose of looping the loop as disclosed in the application aforesaid, additional spring means is provided for 20 increasing the counter-balancing effect on the aeroplane automatically as the latter rises and completely overcoming the weight of the plane when the latter reaches its maximum height (Fig. 3). In the present instance, this means 25 comprises a pair of coiled contractile springs 28 anchored at one of their ends to lugs 29 on a yoke which is apertured at its center to receive the tube section 10 and which abuts against the upper end of the coil 13. The other ends of these 30 springs are adjustably anchored to arms 30 upwardly inclined from the end of the plate 23 opposite the arm 22. The mean line of action of these springs extends substantially longitudinally of the upper end of the coil 13 but when the plane 35 is at rest or flying at a low level, this line of action is disposed somewhat below the horizontal axis about which the tube section 10 tilts. Under this condition the springs actually counteract the 40 lifting action applied to the aeroplane by the coil 13.

The effective length of the coil 13 and the line of action of the springs 28 are adjusted as above described so that the resultant lifting action exerted on the plane in its lowermost position (Fig. 45 2) nearly but not completely overcomes the weight of the plane. Then as the plane rises the effect of the coil 13 decreases but the line of action of the springs 28 moves closer to the tilting axis increasing the lifting action applied to the 50 plane. As the line of action of the springs 28 passes over center relative to the tilting action (see Fig. 3), and the springs thereby augment the force exerted by the coil 13, the entire weight of the aeroplane is overcome and thereafter the 55 springs will continue to maintain the maximum height of the aeroplane while the same is looping or flying at a low speed. If the speed of the plane is increased to the proper degree while the tube section 10 is thus upwardly inclined, the centrifugal force developed will tend to move the tube 60 into horizontal position thereby causing the aeroplane to descend to a lower level in which the counterbalancing action of the springs will no longer overcome the weight of the plane and the 65 latter may make a landing if desired.

The aeroplane propeller is driven by an electric motor generally designated by the numeral 31 housed within the hangar 15 and mounted on a base plate 32 with its shaft 33 vertically disposed 70 and preferably in alignment with the axis of the sleeve 14. The shaft is supported by a thrust bearing 34 and may carry a fan blade 35 to induce circulation of air over the motor parts for cooling them.

75 The upper end of the motor shaft is joined

by a universal coupling extending through the coil 13 to a wire shaft 36 disposed between the tube sections 9 and 10 and having an eye 37 (Fig. 4) beyond the end of the tube section 9 seated in notches 38 in the end of the sleeve 11 on the side 80 of the aeroplane opposite that from which the shaft 36 enters. A driving connection is thereby established between the shaft 36 and the propeller 8.

Preferably the universal coupling is in the form 85 of a helical coil 39 of wire having one end turned onto threads on the upper end of the motor shaft 33 and the other end formed with an eye interengaging with an eye 40 on the end of the wire shaft 36. It will be apparent that with this driving connection thus constructed, the rotary motion of the motor shaft will be transmitted to the propeller at all times during the movement of the aeroplane around its circular path regardless of the height at which the plane may be flying. Flexing of the coil 13 as the plane rises in its flight causes a lengthening of the driving connection tending to force the eye 37 out of the notches 38. To prevent this, a shoulder 41 (Fig. 4) is formed on the wire shaft 36 within the tube 90 section 10 in position to abut against the section 9 when the sections are held in assembled relation by a set screw 42 in a collar 43.

By constructing the tube which supports the aeroplane in two telescoping sections, assembly 105 and dis-assembly of the toy for purposes of shipment or repair are materially facilitated. Thus with the set screws 27 and 42 loosened and the springs 28 unhooked from the arms 30, the sections 9 and 10 may be shortened and the end of 110 the section 10 withdrawn from the coil 13 to enable the eye 40 to be unhooked from the coil 39. The sleeve 26 may then be removed and the tube and the aeroplane separated from the supporting 115 parts.

In order to simulate a commercial aeroplane flying at night, a beacon light 44 rising above the hangar is adapted to direct a beam of light onto the aeroplane as the latter traverses its circular path. To this end the light is adjustably 120 mounted on the upper end of a tower 45, the base of which is secured to the four corners of the plate 23. The beacon light is thus mounted to turn with the aeroplane about the vertical axis of the sleeve 14 and the light from the beacon will play 125 on the aeroplane in its flight around the circular path. Preferably the beacon is supplied with current from the same source as the motor. To this end one terminal of the current supply may be connected to the lamp of the beacon through 130 the metallic parts which support the aeroplane while the other terminal is joined to the lamp by an insulated conductor including a brush 46 engaging a circular contact strip 47 mounted on the flange 21.

From the foregoing it will be apparent that with the mounting herein provided for the aeroplane, the electric motor and all of the parts of the power transmitting connection are enclosed 140 which renders the operation of the aeroplane more realistic. Furthermore, the stator of the motor is stationarily mounted which avoids the use of wiping contacts for carrying the motor current. The result of this construction is that the aeroplane when in operation closely simulates 145 a commercial aeroplane circling around its hangar.

No claim is made herein to the subject matter common to this application and my copending application Serial No. 545,209, filed June 18, 1931, 150

to which the present application is subordinate.
I claim as my invention:

1. In an aeroplane toy, the combination of a miniature aeroplane having a driving propeller, an elongated tube having one end extending into said aeroplane and rotatably supporting the aeroplane to turn about a substantially horizontal transverse axis, a laterally flexible tubular member having one end mounted to turn about a vertical axis and the other end secured to said tube, the intermediate portion of said member being flexible to permit the aeroplane to ascend from and descend to a landing surface while travelling in a circular path about said vertical axis, 80
- 10 a vertical axis and the other end secured to said tube, the intermediate portion of said member being flexible to permit the aeroplane to ascend from and descend to a landing surface while travelling in a circular path about said vertical axis, 85
- 15 an electric driving motor adjacent said vertical axis, and a flexible driving connection between said motor and said propeller extending through said member and said tube. 90
2. In an aeroplane toy, the combination of a miniature aeroplane, an elongated tube disposed in substantially horizontal position and having one end extending into the side of said aeroplane and providing a rotatable support therefor, a casing adapted to be supported on a landing surface for said aeroplane, an electric motor housed within said casing, a sleeve projecting through the top wall of said casing and mounted to turn about a vertical axis, a helical coil of wire having one end secured to said sleeve and the intermediate portion bent to receive one end of said tube at its other end, a shaft operatively connected to the propeller of said aeroplane and extending through said tube, and a helical coil of wire disposed within and extending through 100 said first mentioned coil and providing a universal driving connection between said shaft and the shaft of said motor. 105
3. In an aeroplane toy, the combination of a miniature aeroplane, an elongated tube supporting said aeroplane to turn about an axis extending transversely of the aeroplane body, a flexible tubular member having one end secured to said tube and the other end mounted to turn on a vertical axis, a shaft extending through said tube and having a driving connection with said propeller, and a helical coil of wire extending through 110 said tube and connected to the adjacent end of said shaft, and an electric motor mounted adjacent said vertical axis and having a driving connection with said coil. 115
4. In an aeroplane toy, the combination of a miniature aeroplane, an elongated tube supporting said aeroplane to turn about an axis extending transversely of the aeroplane body, a helical coil of wire detachably secured at one end to said tube and having its other end mounted to turn about a vertical axis, the intermediate portion of said coil flexing to permit the aeroplane to rise and fall in its flight, a shaft extending 120 through said tube and having a driving connection at one end with said propeller, a second helical coil of wire disposed within said first coil and having one end detachably connected to said shaft, an electric motor having a rotary driving connection with the other end of said second coil, the latter serving as a universal coupling between the motor and said shaft. 125
5. In an aeroplane toy, the combination of a miniature aeroplane having a driving propeller, an elongated tube having one end extending into said aeroplane and rotatably supporting the aeroplane to turn about a substantially horizontal transverse axis, a vertical sleeve, a base, two sets of balls having raceways with horizontal and 130 vertical surfaces providing two axially spaced 135
- annular bearings surrounding said sleeve and supporting the same on said base, a flexible tubular member having one end secured to said sleeve and the other end secured to said tube, the intermediate portion of said member being flexible to permit said aeroplane to rise and fall in its flight around the axis of said sleeve, and power driving means for said propeller including a rotary power transmitting connection extending through said sleeve, said member and said tube. 140
6. In an aeroplane toy, the combination of a miniature aeroplane having a driving propeller, an elongated tube having one end extending into said aeroplane and rotatably supporting the aeroplane to turn about a substantially horizontal transverse axis, a vertical sleeve, anti-friction bearings supporting said sleeve and sustaining lateral thrusts exerted thereon, a helical coil of wire having one end received in and secured to said sleeve and the other end receiving the end portion of said tube, the intermediate portion of said coil being flexible to permit the aeroplane to rise and fall in its flight around the axis of said sleeve, a member rigid with said sleeve and having an arm extending transversely of said tube, 145 a surface on said tube cooperating with said member to hold the tube against turning about its own axis while permitting vertical tilting of the tube, and power driving means for said propeller including a rotary power transmitting connection extending through said sleeve, said coil and said tube. 150
7. In an aeroplane toy, the combination of a miniature aeroplane having a driving propeller, an elongated tube having one end extending into said aeroplane and rotatably supporting the aeroplane to turn about a substantially horizontal transverse axis, a flexible tubular member extending in a vertical direction and having its lower end supported to turn about a vertical axis, the upper end of said member being secured to the end of said tube opposite said aeroplane and the intermediate portion being flexible to permit the aeroplane to rise and fall in its flight around said vertical axis, means rotatable with said aeroplane about said vertical axis acting to hold said tube against turning about its own axis, and power driving means for said propeller including a rotary driving connection extending through said member and said tube. 155
8. In an aeroplane toy, the combination of a miniature aeroplane having a propeller, a tube extending into the side of said aeroplane and defining a transverse axis about which the aeroplane turns, means associated with the other end of said tube and supporting the aeroplane for movement in a circular path about a vertical axis and for ascending and descending in its flight around said path, said last mentioned means including a flexible tubular member having one end mounted concentric with said vertical axis to turn about the same and its other end secured to the end of said tube opposite said aeroplane, an electric motor having a stationarily mounted stator, and a driving connection between said propeller and the shaft of said motor including a section disposed within said member and having a universal action. 160
9. In an aeroplane toy, the combination of an elongated tube disposed in a generally horizontal position, a miniature aeroplane rotatably mounted on one end of said tube to turn on a transverse axis, a helical coil of resilient wire tending to maintain itself straight and having one end secured to the end of said tube opposite said aeroplane. 165

plane, means supporting the other end of said coil to turn on a vertical axis, the intermediate portion of the coil being thereby bent so that the coil, acting through the medium of said tube, exerts a lifting action on said aeroplane tending to counter-balance the weight thereof, and power driving means for the propeller of said aeroplane having a rotary driving connection extending through said coil and said tube.

10. In an aeroplane toy, the combination of an elongated tube disposed in a generally horizontal position, a miniature aeroplane rotatably mounted on one end of said tube to turn on a transverse axis, a coiled spring extending in a vertical direction and having its lower end rotatably supported to turn about a vertical axis and one end of said tube received in its upper end, the intermediate portion of said spring being bent whereby to cause a lifting action to be exerted on said aeroplane through the medium of said tube which action decreases as said aeroplane ascends from its landing surface, and a pair of coiled contractile springs disposed on opposite sides of said first mentioned spring and cooperating therewith to exert a resultant lifting action which increases automatically as the aeroplane rises in its flight and at a predetermined level completely overcomes the weight of the aeroplane, and power driving means for the aeroplane propeller having a rotary driving connection extending through said tube.

11. In an aeroplane toy, the combination of an elongated tube disposed in a generally horizontal position, a miniature aeroplane rotatably mounted on one end of said tube to turn on a transverse axis, a coiled spring extending in a vertical direction and having its lower end rotatably supported to turn about a vertical axis and one end of said tube received in its upper end, the intermediate portion of said spring being bent whereby to cause a lifting action to be exerted on said aeroplane through the medium of said tube, an auxiliary spring acting on said tube along a line extending generally longitudinally of the upper bent portion of said coiled spring, said auxiliary spring cooperating with said first mentioned spring to exert a resultant lifting action on said aeroplane which increases automatically as the aeroplane rises in its flight, and power driving means for the propeller of the aeroplane including a driving connection extending through said tube.

12. In an aeroplane toy, the combination of a miniature aeroplane mounted to fly under its tractive effect in a circular path and to ascend and descend from a landing surface, and spring means partially counter-balancing the weight of said aeroplane when the latter is resting on said surface and completely overcoming said weight when the aeroplane reaches a predetermined level.

13. In an aeroplane toy, the combination of means supporting said aeroplane for movement in a fixed circular path and for ascending from and descending to a landing surface in its flight, said last mentioned means including an elongated tube rotatably supporting said aeroplane at one end and a member rotatable about a vertical axis, and spring means acting on the opposite end of said tube and exerting a lifting action on the aeroplane through the medium of the tube, such action partially overcoming the

weight of said aeroplane when said tube is in horizontal position and completely overcoming said weight when the tube is tilted upwardly at a predetermined angle.

14. In an aeroplane toy, the combination of a housing adapted to rest upon a landing surface, a miniature aeroplane, means supporting said aeroplane for movement in a circular path around said housing and to ascend from and descend to said surface including a rotatable member disposed above said housing and rotatable about a vertical axis, a beacon tower rising about said housing and supported by said member, a light carried by said tower and adapted to be directed toward said aeroplane and follow the same in its flight around said path.

15. In an aeroplane toy, the combination of a miniature aeroplane, means supporting said aeroplane to fly in a circular path including a member mounted to turn on a vertical axis and a beacon light carried by said member and adapted to be directed toward said aeroplane so as to play on the plane continuously in its flight around said path.

16. In an aeroplane toy, the combination of a miniature aeroplane, an elongated tube having one end projecting into the side of said aeroplane and rotatably supporting the plane to turn on a transverse axis, a vertically extending flexible tubular member supported at its lower end to turn on a vertical axis, the upper end portion of said member being flexed laterally with the end thereof detachably secured to the end of said tube opposite said aeroplane, a wire shaft substantially equal in length to that of said tube, said shaft being disposed within said tube and having one end projecting beyond the tube and connected to the propeller of said aeroplane, a flexible coupling within said tubular member having one end detachably connected to the opposite end of said shaft, said tube comprising sections adapted to telescope together to afford access to the joint between said shaft and said coupling, and an electric motor having a driving connection with said coupling.

17. In an aeroplane toy, the combination of a miniature aeroplane, an elongated tube projecting into one side of the aeroplane and defining a transverse axis about which the aeroplane is adapted to turn, a sleeve concentric with said tube rotatable in said aeroplane body and having a driving connection with the aeroplane propeller, a shaft extending through said tube and having a connection with said sleeve at a point beyond a said tube, said last mentioned connection being disengageable by axial withdrawal of said shaft from the tube, a flexible tubular member rotatably supported at one end to turn about a vertical axis, the other end of said member being secured to end of said tube opposite said aeroplane, said aeroplane being adapted to rise and fall by flexing of the intermediate portion of said member, a flexible universal coupling extending through said member and connected to said shaft, a driving motor connected to the other end of said coupling, and means limiting the longitudinal movement of said shaft relative to said tube to prevent disengagement of said second connection upon flexing of said member in a direction to lengthen said coupling.

JOHN ESLINGER.
